SHIP'S PROPULSION DEVICE

Henry Mertens, New York, N. Y., assignor to Emil Fries, New York, N. Y.

Application November 7, 1941, Serial No. 418,147

7 Claims. (Cl. 115—29)

My invention relates to a new and useful means for propelling ships or the like craft, and it is the principal object of the invention to provide suitably constructed, engine driven, automatically opening and closing pressure blades on both sides of the ship's stern which remain permanently submerged.

The present, preferred means to propel ships or the like is the customary propeller or screw of manifold construction having any number of blades of desired configuration and pitch. It is however, well known to any marine engineer that such propellers or screws have many disadvantages. Thus, the slip of the propeller, if a certain pressure is required to propel a ship at a given speed, will cause a considerable loss in driving speed and H. P., as well as waste of fuel.

All these disadvantages are positively overcome by my novel pressure blades increasing the driving efficiency to the highest possible degree, and producing the most economical operation, while making every H. P., developed fully used in propulsion.

Another object of my invention is to provide a pressure plate or blade arrangement for the propulsion of water craft and combining therewith a stabilizing means on the outside of the craft in contradistinction to the usual stabilizers as balance tanks, gyroscopes or the like means installed within the ship's hull which by necessity must participate more or less in the ship's movements, while my stabilizers are provided on the outside of the hull without however in any way decreasing the speed and the draft.

Still another object of my invention is the provision of a ship propelling system by means of pressure blades which allow moreover an efficient steering of the vessel if the rudder or steering gear is damaged or out of order.

A further object of my invention is to provide a system of ship's propulsion allowing a readily acting and efficient lubrication.

A still further object of my invention is to provide such a system of ship's propulsion adapted to be electrically operated from the bridge of the ship to effect an instantaneous change in the direction of the propulsion.

My novel and useful propelling system for ships furthermore allows the use of the blades as stabilizers supplementing the actual stabilizers on the stern in order to alleviate and cushion strokes and stamping as well as rolling experienced during heavy seas.

These and other objects and advantages of my

invention will become more fully known as the description thereof proceeds, and will then be specifically pointed out in the appended claims.

In the accompanying drawings forming a material part of this disclosure:

Fig. 1 is a fragmentary, sectional top plan view of a ship's stern equipped with the pressure blades arrangement and a stabilizer plane constructed according to my invention.

Fig. 2 is a side elevation thereof.

Fig. 3 is a sectional elevation of the pressure blades on a somewhat enlarged scale and showing the system of means for reversing their direction of operation.

Fig. 4 is a section on line 4—4 of Fig. 3.

Fig. 5 is a sectional side elevation of one of the pressure blades closed and its operating means, on line 5—5 of Fig. 4.

Fig. 6 is a section on line 6—6 of Fig. 5.

Fig. 7 is a sectional detail view of a modified form of operating means.

As illustrated, the hull 10 of a ship has its stern 11 specially shaped to allow the application of the stabilizing member 12 adapted to equalize the water pressure on top as well as below the member.

The propulsion of the ship is effected by means of two sets of blades generally designated 13 and 14, one set on each side of the stern and oscillating with the shafts 15 and 16 respectively projecting from the stern on each side thereof. Each set of blades is composed of pairwise arranged wings, upper wings 16, 17, and lower wings 18, 19 respectively or vice versa according to the timely position during operation, and the wings of each pair have obliquely disposed outer edges and straight inner edges. The latter being hinged, as at 20, 21 and 22, 23 respectively to a hollow, open shaft 24 having intermediate the pair of wings of the upper and lower wing arrangement a boss 25 secured to shafts 15 and 16 respectively. The inner or closing movement of each pair of wings is limited by means of the substantially triangular members 26 secured to the shaft 24, while their outer opening movements are limited by means of the straight members or elements 27 secured to the outer face of the shaft 24.

The pressure blades are preferably driven by means of a starboard engine generally designated S, and a larboard or port engine generally designated P, and the operating force may be steam, electricity or Diesel motive power etc.

The power plant is connected by the connecting rod 28 to the rock-shaft 29 which is pref-

erably hollow for lubricating purposes as will hereinafter be more fully described.

The rock-shaft is suitably journaled in well lubricated bearings, which are generally designated 30, and extends through the board walls of the ship through water-tight packings 31 into the boss 25 of the shaft 24 for the blades, which carries therein a gear 32 in mesh with the threaded end 33 of the shaft 29.

Within the engine arrangement P a box or container 34, preferably filled with a lubricant is arranged, and the end of shaft 29 extends into this box and carries therein a grease cup 35. Through the end wall of box 34 extends a screw 36 the operation of which displaces the movable box sliding in its frame P, while a collar 37' on the shaft 29 is located in an inner partitioned off space of the frame 37 of the box. This screw extends to the outside of the frame and carries there a large gear 38 and a handled fly wheel 39. The gear 38 meshes with a smaller gear 40 on the shaft of an electric motor 41 which can be operated from the bridge of the ship.

In Fig. 7 I have illustrated a modified form of operating means for the shaft 29 connecting the same by means of a beam 42 or the like with the slides 43, 44, the rods of which operate the pistons 45, 46 within the stuffing boxes 47.

The operation of the propulsion according to my invention will be entirely clear from the above description by having simultaneous reference to the drawings, and it will be clear that upon operation of the slides 48, 49 by the starboard engine S and the port board engine P of the ship, the rock shaft 29 will be imparted an oscillatory movement and the blades will participate in this oscillation, and when moving in the direction of the arrow, Fig. 2 will be alternately opening and closing, their movements being limited by the outer members 27 and by the inner members 26. The reversing of the operation can be effected by the operation of the screw 37 either by hand using the hand-wheel 39 or from the bridge by suitable electrical operation of the motor 41 so that the shaft 29 being connected by its collar 37' to the sliding frame or box 34 will be compelled to follow the direction of oscillation and thus turn the blades in one or the other direction respectively. The box 34 being filled with a lubricant will distribute the same through the bore in the shaft to its bearings and the boss 25 which is watertight.

In cases where the rudder of the ship has been lost or damaged and its gear becomes out of order, the steering of the ship may be effected by the alternate operation of the starboard or port blade arrangement according to prevailing circumstances.

The rock shaft 29 is operated by the intermediary of the slide rods 50 and 51 respectively which are connected to an eccentric on the driving machine.

It will be understood that I have described and shown the preferred form of my ship's propulsion device as one example only of the many possible ways to practically construct the same, and that I may make such changes in the general arrangement of the device and in the construction of its minor details as come within the scope of the appended claims without departure from the spirit of my invention and the principles involved.

Having thus described my invention, what I claim as new, and desire to secure by Letters Patent is:

1. A craft propelling device comprising pairwise arranged engine driven and automatically opening and closing pressure blades on both sides of the craft, means to stabilize the craft, means to lubricate the individual elements of the device, and means to reverse the direction of operation of said pressure blades, said blades acting as emergency means for steering the craft and as stabilizers.

2. A ship propulsion device as described comprising a stabilizing plate surrounding the stern of the ship below the water line, and pressure plates acting as auxiliary stabilizing means and means to steer the ship in cases of emergency, means to secure said stabilizing plate to the ship, and engine driven means to operate the pressure plates.

3. In a ship propulsion device as described, the combination of pressure blades with an engine driven rock shaft to which the shaft of said pressure blades is secured, a hollow cradle for said rockshaft including a lubricating box from which the lubricating means is spread through the hollow shaft by means of a grease cup, a sliding frame in said box having a compartment partitioned off, a collar on said shaft within said compartment, and means to reverse the direction of oscillations of said shaft.

4. In a ship propulsion device as described, sets of pairwise arranged opening and closing pressure blades, means to limit their opening and closing movements, and a means to impart to said blades a reciprocating oscillating movement, said means comprising a rock-shaft, and connections between said rock shaft and an eccentric on the ship's engine, a shaft for said pressure blades to be secured to an outer extension of said rock-shaft, a boss on the shaft of said pressure blades, and a gear on said rock-shaft in mesh with the threaded wall of said boss.

5. In a ship propulsion device as described, two sets of pairwise arranged opening and closing blades one set on each side of the stern, each of the blades of each pair having obliquely disposed outer edges and straight inner edges, a common shaft for each set of blades hollow and open, a boss on said shaft by means of which it is secured to a rock-shaft, hinges for connecting the straight inner edges to said shaft, substantially triangularly-shaped members secured to the inner face of said shaft to limit the inward or closing movements of the blades, and elongated outer members secured to the outer face of said shaft to limit the outward movement of the blades, means to impart to said blades a reciprocating oscillating movement during which one pair of blades of each set is closed and the other open to propel the ship, and a separate drive for each set of blades.

6. In a ship propulsion device as described two sets of opening and closing pressure blades, a rock-shaft to operate each set of pressure blades, bearings for said shaft, and lubrication distributing means to lubricate said shaft and bearings, a shaft for each set of blades, a boss on said shaft having a threaded inner wall, a gear on the rock-shaft in mesh with said threaded wall, slides connected to said rock-shaft and to an eccentric on the driving engine, and means to reverse the rotation of said rock-shaft and pressure blades to oscillate in different directions.

7. In a ship propulsion device as described, a rock-shaft, a support for said shaft including a box for the reception and distribution of lubricant, a slide in said box having a partitioned off

portion, a collar on said shaft in said portioned off portion, and a grease cup at the end of said shaft in said box, a screw for operating said slide and collar to reciprocate the shaft in one direction and in the reverse, gears on said screw and a hand wheel to turn said screw, an electric motor, a gear on the shaft of said motor in mesh with said screw gear to allow a revers-

ing of the rocking direction of the rock-shaft from the bridge and by use of the handwheel, manually, pressure blades operated by the oscillations of said rock-shaft and allowing a steering of the ship in cases of emergency, said pressure blades representing also auxiliary means for stabilizing said ship.

HENRY MERTENS.
